and other long cylindrical objects and the like, and to facilitate the use of such wrenches in confined spaces and to eliminate the binding characteristic of the usual type of pipe wrench due to undesirable friction inherent therein.

UNITED STATES PATENT OFFICE

2,516,395

WRENCH HAVING FLOATINGLY MOUNTED MOVABLE JAW

Delbert C. Kerr, Iowa City, Iowa

Application July 15, 1946, Serial No. 683,629

2 Claims. (Cl. 81—175)

1

This invention relates to tools and more specifically to wrenches particularly adapted for use on pipes or the like, and has for its primary object the provision of a wrench having a fixed and a movable jaw and means for shifting said movable jaw that eliminates the binding characteristic of the usual type of pipe wrench due to undesirable friction inherent therein.

One of the most important objects of this invention is to provide a pipe wrench having a fixed jaw and a movable jaw actuated by a longitudinally disposed, rotatable shaft having an unique jaw-engaging head thereon held in operative engagement with the jaw by a pin that serves also to pivotally mount the movable jaw to assure a positive grip upon the pipe held thereby.

Another important object of this invention is to provide a wrench having a jaw movable toward and from a fixed jaw, which movable jaw is pivotally held in operative position by a collar in encircling engagement therewith and freely slideable on the body of the wrench and the provision of a line contact or abutment on one edge of the movable jaw upon which the same may move as it pivots within the collar.

A still further object of this invention is the provision of a wrench having a pivotally mounted movable jaw that has a cavity formed in one end thereof and so formed to cooperate with a dome-shaped head on an operating shaft therefor, whereby free pivoting movement of the movable jaw is possible as the dome-shaped head rotates in the cavity and bears against said jaw to move the same into operative position.

Another object of this invention is to provide a wrench having a movable jaw with actuating means therefor supported in longitudinal relation to the body of the wrench and projecting beyond the end of the wrench body, the amount of projection being greater when larger work is being engaged so that as the projected end of the actuating member is gripped, greater leverage is obtained.

Other objects of this invention will appear during the course of the following specification, referring to the accompanying drawing, wherein:

Fig. 1 is a side elevation of a wrench made in accordance with the present invention.

Fig. 2 is an edge view thereof.

Fig. 3 is an enlarged, detailed, fragmentary sectional view taken through a portion of the wrench on line III—III of Fig. 2; and

Fig. 4 is a vertical cross sectional view through the wrench taken on line IV—IV of Fig. 1.

The wrench forming the subject matter of this

invention has an elongated, relatively narrow body 6 on one end of which is formed a laterally extending fixed jaw 8. A series of serrations 10 formed along one edge of the jaw 8 co-act with 5 similar serrations 12 on one edge of a movable jaw 14. The thickness of the body 6 and of all the parts about to be described is relatively narrow to facilitate access thereby into recesses or the like not ordinarily possible with the usual type of pipe wrench.

The movable jaw 14 is slidably mounted upon and carried by the body 6 through the medium of a collar 16 which encircles the body 6 and a portion 18 of the jaw 14, which portion 18 has a length substantially the same as the width of collar 16. As clearly illustrated in Fig. 3, a line contact or abutment indicated as at 20 is formed on one edge of the portion 18 remote from the body 6, which abutment 20 bears against one inner wall of the collar 16. A spring 22 yieldably maintains the abutment 20 in position against the collar 16. This collar 16 is of such size to permit free sliding movement thereof on body 6 and to allow the jaw 14 to pivot freely on a pin 24 that passes through portion 18 thereof and through the two side walls of the collar 16. A cavity 26 is formed in the end of the jaw 14 opposite to the serrations 12 and is formed to present a concave bottom wall to cooperate with the rounded portion of a dome-shaped head 32 on one end of an operating shaft 28. An annular groove 30 adjacent to the head 32 is engaged by the pin 24 when the head 32 is within the cavity 26 and against the concave bottom wall thereof. The pin 24 intersects the uppermost portion of the cavity 26 and serves not only to maintain the head 32 within the cavity 26 but pivotally mounts the jaw 14 in the collar 16. Obviously sufficient clearance is provided in the cavity 26 and between pin 24 and groove 30 to permit swinging movement of jaw 14 within collar 16 and on head 32.

A bearing 34 formed integrally with the body 6 receives the shaft 28 in its tapped opening 36, 45 and screw-threads 38 formed on the shaft 28 are in engagement with the internally threaded bearing 34. A bearing 40 disposed near the end of body 6 opposite to the jaw 8 supports the shaft 28 in operative position and establishes a rigid connection for permitting the projected end of the shaft 28 to be used as a working lever when the wrench is being used. A grip 42 is mounted on the free end of the shaft 28 to facilitate rotation of the shaft 28.

It is notable that the wrench may be easily

disassembled if such should become necessary for replacement of worn parts by merely removing the pin 24. When such is done, the jaw 14 is slipped from engagement with the collar 16 and the shaft 23, and the collar 16 slipped over the fixed jaw 9. The length of the collar 16 and the rounded point of merger between the jaw 8 and the body 6 as is clear in Figs. 1 and 2, readily permits such removal of the collar 16.

Frictional binding is almost entirely eliminated by the provision of the concave bottom wall in the cavity 26 which permits pivotal movement of the jaw 14 as this bottom wall slides transversely across the face of the dome-shaped head 32. This action takes place even when a great amount of pressure is brought to bear against this bottom wall by the shaft 28.

It is understood that wrenches having physical characteristics other than those shown and described might be made without departing from the spirit of the invention or scope of the appended claims.

Having thus described my invention, what I claim as new and desire to secure by Letters Patent is:

1. A wrench of the character described comprising a body having a fixed jaw extending laterally therefrom; a collar slidably carried by the body; a movable jaw pivotally mounted in said collar, said movable jaw having a cavity formed in its rear end, with the bottom wall thereof being concave; an internally threaded bearing depending from one edge of said body; an operating shaft in threaded engagement with said bearing, said shaft having a dome-shaped end engaging the concave bottom wall of said cavity and an annular groove formed therein adjacent said dome-shaped end; and a pin for pivotally mounting said movable jaw in said collar, said pin intersecting said cavity and passing tangentially through said annular groove for maintaining the shaft and movable jaw in operative engagement, said movable jaw having an abut-

ment formed on one edge thereof and bearing against a proximal wall of the collar as the movable jaw swings on said pivot.

2. A wrench of the character described comprising a body having a fixed jaw extending laterally therefrom; a collar slidably carried by the body; a movable jaw pivotally mounted in said collar, said movable jaw having a cavity formed in its rear end, with the bottom wall thereof being concave; an internally threaded bearing depending from one edge of said body; an operating shaft in threaded engagement with said bearing, one end of said shaft having a dome-shaped head in slidable engagement with the concave bottom wall of said cavity and having an annular groove formed therein adjacent said dome-shaped end; a pin for pivotally mounting said movable jaw in said collar, said pin intersecting said cavity and passing tangentially through said annular groove for maintaining the shaft and movable jaw in operative engagement, said movable jaw having an abutment formed on one edge thereof and bearing against a proximal wall of the collar as the movable jaw swings on said pivot.

3. A wrench of the character described comprising a body having a fixed jaw extending laterally therefrom; a collar slidably carried by the body; a movable jaw pivotally mounted in said collar, said movable jaw having a cavity formed in its rear end, with the bottom wall thereof being concave; an internally threaded bearing depending from one edge of said body; an operating shaft in threaded engagement with said bearing, one end of said shaft having a dome-shaped head in slidable engagement with the concave bottom wall of said cavity and having an annular groove formed therein adjacent said dome-shaped end; a pin for pivotally mounting said movable jaw in said collar, said pin intersecting said cavity and passing tangentially through said annular groove for maintaining the shaft and movable jaw in operative engagement, said movable jaw having an abutment formed on one edge thereof and bearing against a proximal wall of the collar as the movable jaw swings on said pivot, said collar being in encircling engagement with said body and a portion of said movable jaw; and a spring interposed between the body and the opposite edge of said movable jaw for cooperating with the shaft in yieldably maintaining the abutment in engagement with the said wall of the collar.
